DESIGN FOR A FLOOR WAXER

Emmett C. Hartley, Euclid, Ohio, assignor to The Sherwin-Williams Company, Cleveland, Ohio,
a corporation of Ohio

Application June 18, 1947, Serial No. 139,785

Term of patent 14 years

(Cl. D9—2)

To all whom it may concern:

Be it known that I, Emmett C. Hartley, a citizen of the United States, residing at Euclid, county of Cuyahoga, and State of Ohio, have invented a new, original, and ornamental Design for a Floor Waxer, of which the following is a specification, reference being had to the accompanying drawing, forming a part thereof.

Fig. 1 is a perspective view of my floor waxer with the handle being broken away to indicate greater length thereof;

Fig. 2 is a side elevation of the same;

I claim:

The ornamental design for a floor waxer, as shown and described.

EMMETT C. HARTLEY.
